(57) CLAIM

The ornamental design for a beverage dispenser, as shown and described.

DESCRIPTION

FIG. 1 is a perspective view of the present invention beverage dispenser;

FIG. 2 is a perspective view thereof with its shelf in a horizontal position;

FIG. 3 is front view thereof;

FIG. 4 is a perspective view thereof shown the design in exploded condition;

FIG. 5 is a rear perspective view broken away for ease of illustration with the handle pushed in;

FIG. 6 is a rear perspective view broken away for ease of illustration with the handle pulled out; and,

FIG. 7 is a bottom view thereof.

The broken lines in the drawings are included for the purpose of illustration and form no part of the claimed design.
